UNITED STATES PATENT OFFICE.

EDGAR E. SHELLEY, OF NEWARK, NEW JERSEY, ASSIGNOR TO THE ECONOMY PAPER COMPANY, OF NEWARK, NEW JERSEY, A CORPORATION OF NEW JERSEY.

PAPER-TOWEL-VENDING MACHINE.

Application filed July 21, 1922. Serial No. 576,431.

To all whom it may concern:

Be it known that I, EDGAR E. SHELLEY, a citizen of the United States, and residing at Newark, in the county of Essex and State of New Jersey, have invented certain new and useful Improvements in Paper-Towel-Vending Machines, of which the following is a specification, such as will enable those skilled in the art to which it appertains to make and use the same.

This invention relates to machines for vending paper towels, napkins and the like and particularly to machines of this class employing coin actuated means for controlling the vending of the towels, napkins or the like and the object of the invention is to provide a machine of the class specified comprising a drum rotatably mounted in a suitable casing with a cutter device mounted in juxtaposition to said drum and cooperating therewith for cutting predetermined portions or sections of paper from a roll of paper mounted in the machine; a further object being to provide coin controlling means for actuating said drum to permit of the vending of the paper from said roll of paper; a further object being to provide means for intermittently rotating the drum in said casing or to rotate said drum independent of said intermittent feeding means; and with these and other objects in view the invention consists in a machine of the class and for the purpose specified which is simple in construction and operation, efficient in use and which is constructed and operated as herein-after described and claimed.

The invention is fully disclosed in the following specification, of which the accompanying drawings form a part, in which the separate parts of my improvement are designated by suitable reference characters in each of the views, and in which:—

Fig. 1 is a front view of my improved machine.

Fig. 2 is a side view of the machine shown in Fig. 1 with the side plate removed and with parts broken away and in section.

Fig. 3 is a longitudinal, partial, section view through the machine with parts of the construction broken away and in section.

Fig. 4 is a view similar to Fig. 2 but looking from the opposite side of the machine and only showing part of the construction.

Figs. 5, 6 and 7 are sectional detail views

of parts of the construction which I employ and indicating different positions assumed by said parts in the operation of the machine.

Fig. 8 is a view similar to Fig. 2 but showing only a part of the construction; and

Fig. 9 is a detail sectional view of a part of the construction which I employ.

My improved machine is designed for the purpose of vending a sheet of paper of predetermined dimensions for use as a towel, napkin or the like by the insertion of a coin into the machine for controlling the vending of such paper and, in practise, I provide a suitable box-shaped casing 10 which is closed at the sides, back, top and bottom, the bottom of the casing being provided with a coin receptacle 11 hinged to the casing as shown at 12 and provided with a lock 13 for controlling the opening and closing of the receptacle 11. The front of the casing is provided with a door 14 adapted to be swung upon a transverse rod 15 and held in a closed position by a rod 16 passed through a beaded portion 17 at the top of the cover and through the sides of the casing 10, said rod being provided at one end with a head 18 and being apertured to receive a padlock 19 on the other end thereof. The cover 14 is also provided centrally with a glass panel 20 and at one side thereof with a coin aperture 21. Between the compartment 11 and the hinged end of the cover 12, the bottom of the casing is provided with a transverse discharge opening 22 through which the paper from a roll 23 is adapted to pass.

The roll of paper 23 is mounted upon a heavy shaft 24 which is slidably mounted in tracks or runways 25 on the inner faces of the side walls of the casing as clearly shown in Figs. 2, 3 and 4 of the drawing.

Mounted in the lower portion of the casing 10 is a frame 26 comprising substantially V-shaped side plate members joined by three rods 27 and one of said plate members is provided with an upwardly and forwardly directed coin chute 28 the face of which is adapted to abut the inner face of the cover 14 in juxtaposition to the coin aperture 21 and the frame 26 is supported in the casing by reason of the shape thereof and the keying of said frame to lugs 29 which enter recesses 30 in the side plates of said frame.

The operative mechanism of my improved

machine is all mounted in connection with the frame 26 to permit of the placement of said mechanism in the machine and the removal thereof from the machine, for repair or other purposes and in practice I provide a shaft 31 which is fixed in the frame 26, and rotatably mounted on said shaft between the side plates of the frame is a drum 32 of tubular construction and provided with 10 end plates 33 and 34 of openwork or web-like construction. The drum 32 is provided with a rough facing such as emery cloth or the like and at a predetermined point with a longitudinal aperture 35 which is opened 15 inwardly through the drum and the side walls of the aperture are reinforced by metal facing sheets 36.

The end plate 33 of the drum is provided with a plurality of projecting annular flange 20 members 37 as clearly shown in Fig. 4 of the drawing, said members being cut away at intervals and provided where cut away with projecting pins 38. A shaft 39 is mounted longitudinally of and in front of 25 the drum 32 and is rotatable in the side plates of the frame 26, said shaft being provided with a cutter blade 40 having projecting teeth 41 and a central aperture portion 42 as shown in Fig. 3 of the drawing and 30 secured to the shaft 39 at one end thereof is a geneva 43 having four substantially arc-shaped or concave surfaces 44 adapted to operate in connection with the flange members 37 and in the corner portions of the 35 geneva are three elongated apertures 45 in connection with which the pins 38 are adapted to operate for intermittently rotating said shaft and the cutter blade 40.

It will be noted that the roll of paper 23 40 rests upon the top of the drum 32 and the paper is fed by the rough surface of said drum when the drum is rotated and pivotally mounted in connection with the inner faces of the side walls of the casing 10 are 45 two lever arms 46 the free ends of which carry a transverse roller 47 which is adapted to bear upon the periphery of the drum 32 in juxtaposition to the shaft 39 and a spring 48 is mounted on the shaft 39 centrally there- 50 of and cooperates with the roller 47 to tensionally hold said roller in engagement with the drum.

Secured to the shaft 31 within the drum 32 and in juxtaposition to the end plate 34 55 thereof is a cam 49 and pivotally mounted in connection with the plate 34 as shown at 50 is a lever 51 which carries a roller 52 which operates in connection with the cam 49. A spiral spring 53 is connected with 60 the shaft of the roller 52 and with the plate 34 as shown at 54 and serves to normally hold the roller in engagement with the face of the cam at all times. Another lever 55 is pivoted to the plate 43 as shown at 56 65 and is provided with a spring 57 for nor-

mally holding the same in engagement with the free end of the lever 51 and said lever 55 is provided with a projection 58 adapted to engage a pin 59 for intermittently operating said lever or moving the same out of 70 engagement with the lever 51 as hereinafter set out.

Rotatably mounted on the shaft 31 outwardly of the plate 34 of the drum 32 is a disk 60 provided at a predetermined point 75 in the periphery thereof with a coin receiving recess 61 into which a coin, through the coin chute 28, is adapted to pass and this recess normally registers with the coin chute when the machine is in an inoperative position. The disk 60 is provided on its inner face with a projecting pin 62 which cooperates in an elongated aperture 63 in the plate 34 of the drum to interlock the disk 60 with said drum and outwardly of the disk 85 60 is a segmental disk 64 which is also rotatably mounted on the shaft 31 and is provided with a flange 65 which overlaps the periphery of the disk 60 or a predetermined area thereof and the segmental disk 61 is 90 coupled with a crank lever 66 through a pin 67 said lever being mounted outwardly of the side wall of the casing 10 and the pin 67 passes therethrough. The lever 66 is held in position by a screw 68 which passes 95 into one end of the shaft 31 and mounted on said shaft is a spring 69 one end of which is passed around the pin 67, and the other end of which is secured to one side plate of the frame 26 as shown at 70 in Fig. 2 of the 100 drawing.

The outer face of the disk 60 is provided with a plurality of inwardly projecting teeth 71 in connection with which a pawl 72 pivoted to the segmental disk 67 as shown 105 at 73 is adapted to operate and a spring 74 is adapted to normally hold the pawl in an outward position to engage said teeth or projection 71, and the segmental disk is provided with a projection 75 for holding the 110 free end of the pawl in operative position and for preventing the displacement thereof. One side wall of the casing 10 is provided on its inner face with an arc-shaped 115 projecting flange 76 which serves to cooperate with the disk 60 to retain the coin against displacement therefrom or from the recess 61 thereof until the coin is over the coin receptacle 11 as shown in Fig. 8 of the drawing.

Mounted on the shaft 31 within the drum 32 and in juxtaposition to the plate 33 is a collar 77 having a recess 78 in the periphery thereof and a pawl 79 is pivotally mounted in connection with the plate 33 of the drum and normally held in engagement 120 with the collar 77 by a spring 80 and this construction serves to prevent the backward rotation of the drum when the same reaches its normal or inoperative position.

The disk 60 is provided on its inner face 125

and adjacent to the periphery thereof with a projecting pin 81 which is adapted to operate in connection with a raised portion 82 on a lock lever 83 rotatably mounted on one of the rods 27 and provided at its free end with a part 84 adapted to cooperate with a recess 85 on the periphery of the side plate 34 of the drum, said lever being held in engagement with the drum by a suitable 10 spring 86.

It will be understood from the foregoing description that the machine is normally inoperative until a coin has been inserted into the machine through the aperture 21. In other words, by moving the crank 66 forwardly and downwardly the segmental disk 64 will be correspondingly moved but the drum 32 and the disk 60 will remain stationary. Upon the insertion of a coin however, into the machine, the coin will drop into the recess 61 and by manipulating the crank 66 as above set out, the flange 65 will engage the coin in the recess 61 and cause the disk 60 to be rotated and the drum 32 to be correspondingly operated.

It will be understood that the drum is held against rotation by the engagement of the lock lever 83 therewith but in the above described operation and upon the insertion of the coin into the disk 60 or the recess 61 therein, as said disk is rotated, the pin 81 operates to move the lever 83 into an inoperative position in which operation, the pin 62 moves freely in the elongated aperture 63 in the side plate 34 of the drum and said drum remains stationary and as the movement of the crank lever 66 is continued the drum 32 will be rotated a partial revolution, approximately a one-quarter revolution which will be the movement of the crank lever 66. Upon releasing the crank lever 66, the same will be returned to its normal position by the spring 69 and this operation may be repeated until the drum has completed one revolution and in the last named operations, the pawl 72 engages the projecting teeth 71 to rotate the drum as well as the disk 60.

It will be understood that in the above operation of rotating the drum, the geneva 43 will be intermittently rotated to correspondingly rotate the cutter blade 40 by the engagement of the pins 38 with the apertures 45 of the geneva and the successive steps of this operation are shown in Figs. 4, 5, 6 and 7 of the drawing. In the last fraction of the revolution of the drum 32 the cutter blade 40 passes into the aperture 35 in the drum and cuts or tears the paper passed thereover to cut a predetermined portion of the paper from the roll of paper 23 and at the end of this operation the drum will be retained in its normal position ready for another operation.

In the above operation it will also be ap-

parent that the coin passed into the machine is carried around with the disk 60 until it is over the receptacle 11 into which the coin drops and from which the coin or coins may be removed by opening the door to said receptacle through the lock 13.

In the above operation of rotating the drum it will also be understood that the roller 52 on the lever 51 travels over the cam face of the cam 49 and in the first cranking operation the roller travels upwardly over the raised portion 49^a of the cam and places the spring 53 under tension as clearly shown in Fig. 5 of the drawing and the lever 55 in this position drops beneath the lever 51 and serves to support said lever and to relieve the tension of the spring 53 to permit if desired, the withdrawal of the paper from the machine by hand and the rotation of the drum and various other parts of the machine by the operator in withdrawing the paper without manipulating the crank after the first manipulation thereof. When the roller 52 reaches the position shown in Fig. 7 on the face of the cam 49 the lever 55 is moved into inoperative position by the projection 58 to allow the sudden dropping of the lever 51 to impart a sudden rotary action to the drum 32 in the operation of passing the cutter blade 40 into and out of the aperture 35 in the drum 32 in the operation of cutting or tearing the paper.

It will be understood that the pawl 79 operates to prevent the backward movement or rotation of the drum 32 when it reaches its normal position and the recess 49^b in the cam 49 will also operate to hold said drum in stationary position after completing one cycle of the operation and while I have shown certain details of construction for carrying my invention into effect it will be understood that I am not necessarily limited to these details, and various changes therein and modifications thereof may be made within the scope of the appended claims without departing from the spirit of my invention or sacrificing its advantages.

Having fully described my invention, what I claim as new and desire to secure by Letters Patent, is:

1. A machine of the class described comprising a suitable casing, a drum rotatably mounted in said casing and provided with an elongated aperture, a rotatable cutter device mounted in juxtaposition to and longitudinally of said drum and adapted to cooperate with the aperture of said drum, means involving a crank lever for controlling the rotation of said drum, means for normally holding said drum against rotation, coin controlling means for moving said last named means into inoperative position to permit of the rotation of said drum, and means for imparting a sudden rotary movement to said drum and said cut-

ter device in the passage of said cutter device into and out of the aperture in said drum.

2. A machine of the class described comprising a suitable casing, a drum rotatably mounted in said casing and provided with an elongated aperture, a rotatable cutter device mounted longitudinally of the drum and in operative connection therewith and adapted to be rotated by said drum, the blade of said device being adapted to operate in connection with the aperture in said drum, a crank lever at one side of the casing and normally out of engagement with said drum, and means for coupling said crank lever with said drum.

3. A machine of the class described comprising a suitable casing, a drum rotatably mounted in said casing and provided with an elongated aperture, a rotatable cutter device mounted longitudinally of the drum and in operative connection therewith and adapted to be rotated by said drum, the blade of said device being adapted to operate in connection with the aperture in said drum, a crank lever at one side of the casing and normally out of engagement with said drum, means for holding said drum against movement, and means for coupling said crank lever with said drum.

4. A machine of the class described comprising a suitable casing, a drum rotatably mounted in said casing and provided with an elongated aperture, a rotatable cutter device mounted longitudinally of the drum and in operative connection therewith and adapted to be rotated by said drum, the blade of said device being adapted to operate in connection with the aperture in said drum, a crank lever at one side of the casing and normally out of engagement with said drum, means for holding said drum against movement, means for coupling said crank lever with said drum, and means whereby the insertion of a coin into the machine will cause the drum locking means to be moved into inoperative position and complete the coupling between said crank lever and said drum to permit of the rotation of said drum.

5. A machine of the class described comprising a suitable casing, a drum rotatably mounted in said casing and provided with an elongated aperture, a rotatable cutter device mounted longitudinally of the drum and in operative connection therewith and adapted to be rotated by said drum, the blade of said device being adapted to operate in connection with the aperture in said drum, a crank lever at one side of the casing and normally out of engagement with said drum, means for holding said drum against movement, means for coupling said crank lever with said drum, means whereby the insertion of a coin into the machine will cause the drum locking means to be moved

into inoperative position and complete the coupling between said crank lever and said drum to permit of the rotation of said drum, and means whereby the drum may be intermittently rotated by said crank lever to complete one revolution thereof.

6. A machine of the class described comprising a suitable casing, a drum rotatably mounted in said casing and provided with an elongated aperture, a rotatable cutter device mounted longitudinally of the drum and in operative connection therewith and adapted to be rotated by said drum, the blade of said device being adapted to operate in connection with the aperture in said drum, a crank lever at one side of the casing and normally out of engagement with said drum, means for holding said drum against movement, means for coupling said crank lever with said drum, means whereby the insertion of a coin into the machine will cause the drum locking means to be moved into inoperative position and complete the coupling between said crank lever and said drum to permit of the rotation of said drum, means whereby the drum may be intermittently rotated by said crank lever to complete one revolution thereof, and means cooperating with the drum for imparting a sudden rotary movement thereto and to said cutter device when the blade of the cutter device passes into and out of the aperture of said drum.

7. A machine of the class described comprising a suitable casing, a drum rotatably mounted in said casing and provided with an elongated aperture, a rotatable cutter device mounted longitudinally of the drum and in operative connection therewith and adapted to be rotated by said drum, the blade of said device being adapted to operate in connection with the aperture in said drum, a crank lever at one side of the casing and normally out of engagement with said drum, means for holding said drum against movement, means for coupling said crank lever with said drum, means whereby the insertion of a coin into the machine will cause the drum locking means to be moved into inoperative position and complete the coupling between said crank lever and said drum to permit of the rotation of said drum, means whereby the drum may be intermittently rotated by said crank lever to complete one revolution thereof, means cooperating with the drum for imparting a sudden rotary movement thereto and to said cutter device when said cutter device cooperates with said drum, and means for preventing backward rotary movement of the drum when in its normal position.

8. A machine of the class described comprising a suitable casing, a frame detachably mounted in the casing, a drum rotatably mounted in said frame, said drum being pro-

vided with a longitudinal aperture in the periphery thereof, a cutter blade rotatably mounted in said frame, means on said drum cooperating with a Geneva member for imparting intermittent rotary movement to said cutter blade in the rotation of said drum and coin controlled means for controlling the rotation of said drum.

9. A machine of the class described comprising a suitable casing, a frame detachably mounted in the casing, a coin-controlled drum rotatably mounted in said frame, said drum being provided with a longitudinal aperture in the periphery thereof, a cutter blade rotatably mounted in said frame, means on said drum cooperating with a Geneva member for imparting intermittent rotary movement to said cutter blade in the rotation of said drum, and means for imparting sudden rotary movement to said drum and said cutter blade when said cutter blade passes through the aperture of said drum.

10. A machine of the class described, comprising a suitable casing, a drum coin-controlled rotatably mounted in said casing and provided with an elongated aperture, a rotatable cutter device mounted in juxtaposition to and longitudinally of said drum, means on said drum and said cutter device, whereby intermittent rotary movement is imparted to said cutter device on the rotation of said drum, means involving a cam for imparting sudden rotary movement to said drum and cutter device, when said cutter device cooperates with the aperture of said drum.

11. A machine of the class described, comprising a suitable casing, a drum rotatably mounted in said casing and provided with an elongated aperture, a rotatable cutter device mounted in juxtaposition to and longitudinally of said drum, means on said drum and said cutter device, whereby intermittent rotary movement is imparted to said cutter device on the rotation of said drum, means for rotating said drum, means involving a cam for imparting sudden rotary movement to said drum and cutter device, when

said cutter device cooperates with the aperture of said drum, and coin controlled means for controlling the rotation of said drum.

12. A machine of the class described comprising a casing, a drum rotatably mounted in the casing, a cutter blade mounted in juxtaposition to and longitudinally of the periphery of said drum and adapted to cooperate with an aperture therein, said cutter blade being placed in operative connection with said drum through a Geneva member whereby in the rotation of said drum, said cutter blade will be intermittently rotated, and means involving a crank for rotating said drum.

13. A machine of the class described comprising a casing, a drum rotatably mounted in the casing, a cutter blade mounted in juxtaposition to and longitudinally of the periphery of said drum and adapted to cooperate with an aperture therein, said cutter blade being placed in operative connection with said drum through a Geneva member whereby in the rotation of said drum, said cutter blade will be intermittently rotated, and means involving a crank for rotating said drum, said crank being normally out of engagement with said drum, and coin controlled means for coupling the crank with said drum.

14. A machine of the class described comprising a casing, a drum rotatably mounted in the casing, a cutter blade mounted in juxtaposition to and longitudinally of the periphery of said drum and adapted to cooperate with an aperture therein, said cutter blade being placed in operative connection with said drum through a Geneva member whereby in the rotation of said drum, said cutter blade will be intermittently rotated, and means involving a crank for rotating said drum, said crank being normally out of engagement with said drum, coin controlled means for coupling the crank with said drum, and means for normally retaining the drum in predetermined position.

In testimony that I claim the foregoing as my invention I have signed my name this 14th day of July, 1922.

EDGAR E. SHELLEY.
